SHARPENER FOR CLOTH CUTTING MACHINES

John B. Gury, Jr., Richmond Heights, Mo., assignor to J. B. Gury Mfg. Co., St. Louis, Mo., a corporation of Missouri

Application March 31, 1941, Serial No. 336,004

10 Claims. (Cl. 51—246)

The present invention relates to sharpening mechanism in cloth cutting machines wherein a vertically reciprocating blade is employed.

The object of this invention is to provide an efficient sharpener for a cloth cutting machine of the type which has a vertical reciprocating knife.

The present invention includes improved means by which such a sharpener may be driven by the motor of such a machine. It includes means by which the motor is connected automatically to drive the sharpener when the pressure foot bar is placed in lowermost position.

Improved driving mechanism is provided by the use of extended splined shafts so that the sharpener is driven while it is moved vertically along the knife.

The sharpener is so arranged that the maximum of the driving mechanism is away from the sharpener. Abrasive materials from the sharpener have a tendency to lodge on adjacent parts and cause troublesome wear, if those parts are such as to require close fitting.

Novel sharpening mechanism including non-circular resilient pulleys for abrasive belts is provided which gives the best results for a knife of the character herein and most nearly simulates the edge provided when a knife is sharpened manually by a skilled operator.

Other objects will be apparent from the following detail description of an embodiment of this invention, taken with the accompanying drawings.

Similar reference characters designate like parts throughout the drawings, in which—

Fig. 1 is a side elevational view, partly in section, of a cloth cutting machine with my improved blade sharpening mechanism mounted thereon in operative position;

Fig. 2 is a vertical sectional view taken on line 2—2, of Fig. 1;

Fig. 3 is a front elevation of Fig. 1, the lower portion being broken away;

Fig. 4 is a vertical sectional view on the line 4—4, Fig. 3, illustrating clutch details;

Fig. 5 is a vertical sectional view on line 5—5, Fig. 3, illustrating a bearing arrangement and helical gear mounting;

Fig. 6 is a horizontal section on line 6—6, Fig. 3, on an enlarged scale;

Fig. 7 is a similar view on line 7—7, Fig. 3, illustrating the means whereby the presser foot bar is held stationary during sharpening and cutting operations;

Fig. 8 is a plan of the sharpening mechanism

in operative position, the view being taken on line 8—8, Fig. 3;

Fig. 9 is a fragmentary view similar to Fig. 3, on an enlarged scale showing the sharpening mechanism clamped in open position;

Fig. 10 is a plan view of said mechanism, the view being taken on line 10—10, Fig. 9, and showing in detail a clamping arrangement;

Fig. 11 is a sectional view on the line 11—11, Fig. 9;

Fig. 12 is a bottom plan view of the sharpening assembly, the view being indicated by line 12—12, Fig. 3;

Fig. 13 is a fragmentary view similar to Fig. 1, illustrating the sharpening assembly clamped in its inoperative position immediately following a sharpening operation;

Fig. 14 is a vertical section on line 14—14, Fig. 10;

Fig. 15 is a similar view on line 15—15, Fig. 8;

Fig. 16 is an enlarged fragmentary view similar to Fig. 8, illustrating a condition obtaining at one stage of the sharpening operation;

Figs. 17 and 18 are respectively a plan and a side elevation of a resilient pulley member as it appears before its adaptation to the present invention; and

Figs. 19 and 20 are similar views of a pulley hub illustrative of one of several configurations contemplated.

With particular reference to Fig. 1, the sharpening assembly A is shown embodied in a cloth cutting machine B of well known design.

The base C thereof, is supported by rollers (not shown) whereby the machine may be operated along a flat surface supporting a lay of cloth or similar material.

A vertically reciprocating cutting knife D, slidably supported in a column or standard E extending upwardly from said base, is operated by means of a crank pin F and associated connecting rod G, the source of power being a motor H having a fly-weight H¹, fixed to its shaft J.

During cutting operations the position of the vertically adjustable bar K, which carries the presser foot member M, is manually determined by means of the locking and releasing linkage N as shown, or by similar means. A description of the expedient illustrated will appear hereinafter. An appropriate handle is provided for manipulating the machine.

Excluding the sharpening mechanism A, machines of the character thus far described are well known in the art, and further detailed description is deemed unnecessary.

The sharpening assembly A is slidably mounted on the presser foot bar K in such manner that the blade D may be sharpened from end to end. Said assembly includes a carriage 1, provided with a hub portion 2 through which the bar K extends, said hub having a polygonal opening 3 slightly larger than the exterior contour of said bar, the latter also being polygonal in horizontal cross section.

A thumb and index finger extension 4 is integral with said carriage, as are also two depending tubular cylindrical portions 5. Rotatively sleeved on each of the latter is the hub portion 6 of a pair of twin plates 7, each provided with an opening through which passes a hollow shaft 8 secured against rotation by a nut 9 (Fig. 14).

Mounted on each shaft 8 between a shoulder 10 thereon, and properly spaced by a sleeve 11 held in place by a cap screw 12 as shown, is a pulley construction generally indicated by the numeral 13. Each pulley includes a non-circular annular tire 14 of resilient material having a plurality of spaced apertures 15, for reasons later explained. Obviously any one of a number of resilient materials may be employed, but I have found by tests that synthetic rubber rings, such as illustrated in Figs. 17 and 18, are most satisfactory. It is noted that the outer periphery of such rings is convex as at 16, and that prior to mounting on the sharpening device the rings are circular.

An inspection of Figs. 11 and 14 is invited to clarify the manner in which the circular body of Fig. 17 is mounted on the sharpener A, so that it assumes a non-circular configuration in accordance with my invention.

At 17 is shown a rectangularly contoured metal hub, the distance between whose diametrically opposed corners is slightly greater than the inside diameter of a ring or tire 14. Said corners 40 are rounded as shown at 18. The resilient circular body 14 is forced over a member 19 and clamped in place between an annular flange 19 thereon and a circular plate 20 secured to the member 17 by removable screws, as shown in Fig. 14. An additional spacer sleeve 21 of proper length is interposed between the upper surface of said member and the aforementioned shoulder 10. As is apparent each pulley structure 13 is freely rotatable on its shaft 8.

With reference to the resilient pulley bodies it is to be noted that the deformation thereof is slight. The rounded corners 18 facilitate the entry of the polygonal member, as do the apertures 15, but neither of them is indispensable. The embodiment shown however is preferable, since the rounded corners 18 eliminate any tendency to cut into the body and the perforations 15 increase its resiliency. Attention is also directed to the ease with which a defective or worn out pulley may be removed and repaired or replaced, by removal of the screw 12 and the sleeve 11.

I have found by experiment that the best results are obtained with my sharpener when non-identical peripheries are provided in an associated pair of pulleys. Thus, as shown in Fig. 11, one pulley body 14 may be mounted on a pentahedral member 17a, thereby producing an ideal arrangement. To maintain the pulleys in proper spaced relationship their supporting plates 7 are provided with semi-circular intermeshing racks 22, movement of the plates being had by manipulation of a lug or finger piece 23. The finger piece or lug 23 is formed integrally with

one of a pair of abutments 24, one of which is clamped on each plate 7 by the nut 9. The abutments 24 cooperate with spring-pressed ball devices 25, fixed in the carriage 1 and adapted to maintain the arms 7 and the pulley assemblies in a stationary out-of-the-way position when the sharpener is not in use, as shown in Fig. 10.

Novel means to drive the sharpening mechanism A simultaneously with the knife D is provided. It includes a disc 26 driven by the motor shaft J, and a disc 27 integral with a boss 28, the latter having an integral helical gear 29 formed thereon, all located in the upper portion of a housing 30 secured to the motor by screws 31. The two discs form a clutch automatically disengaged during cutting operations, and also automatically engaged during sharpening operations by means to be later described.

As best shown in Figs. 1, 2 and 6, the motor driven disc 26, knife reciprocating rod G and flyweight are connected by crank pin F, with suitable spacers being provided where necessary to maintain proper alignment. The disc 26 is provided centrally thereof with a circular recess to accommodate the head of a screw 33 threaded in the end of a shaft 34, the head of the screw forming an end bearing to hold the disc 27 on that shaft. The shaft 34 is journaled in a sleeve 35 which is press-fitted or otherwise fixed within the boss 28.

During cutting operations, the disc 27 is disengaged from the disc 26 by means of a leaf spring assembly 36, later to be described. At such time the disc 26 merely revolves about the head 33 and the presser foot bar K occupies an elevated position, such as suggested by the broken lines in Fig. 1.

The leaf spring assembly, as shown in the drawings, is composed of three components, two of which are fixed in the housing 30 by means of a screw 37. One component designated 38 bears against the other designated 39 normally forcing it to the right, as shown in Fig. 4. The shaft 34 is firmly attached, as by riveting, to the upper end of the spring leaf 39. This permits a slight space to obtain between the clutch disc when the third leaf spring 40 is free by reason of the elevated position of the bar K and its clutch operating elements, generally indicated at 41.

To facilitate clutch engaging and disengaging operations, the member 40 is provided with an off-set portion 42, which, as shown, lies in the vertical path of a roller 43, rotatable on a pin 44 supported in the bifurcated ends 45 of a horizontal element 46 clamped in predetermined position on the bar K by a screw 47. Since Fig. 4 clearly illustrates the engaged position of the clutch, it is thought unnecessary to specifically illustrate the disengaged position.

Necessarily, in order to sharpen the knife D, the presser foot occupies the lowered position shown in Fig. 1, while during cutting operations it occupies an elevated position. No claim is made to the structure N herein illustrated by which this is accomplished; and which includes a manually operable lever arm 48 adjacent the handle O, pivoted at 49 and having a bifurcated portion 50 engaging a pin 51 of a sliding bolt 52 adapted to enter notches 53 formed in bar K. A spring 54, or other expedient, may be employed to maintain the bar in desired position. The bar K is raised and lowered manually by an integral extension 55 of the member 46.

The motor shaft J, fly-weight H', disc 26, disc 27 and helical gear 29, all rotate clockwise. How-

ever it is necessary for the pulley assemblies 13 to rotate in opposite directions to one another, and each pulley is independently driven, dual drive shafts 56 being employed. The shafts 56 are rectangular in cross section as shown, or splined to have a vertically sliding fit within a pair of helical gears 57 as well as within their integral, depending exteriorly cylindrical portions 58.

The helical gears 57 disposed at right angles to the gear 29 loosely intermesh with the latter, so that when the clutch engaging leaf spring assembly 36 is free the disc 26 automatically effects a separation between itself and the disc 27. Each sleeve 58 is rotatably supported in bushings 59 and suitable openings 60 are provided in the housing 30 through which the dual shafts 56 extend. Protective elongated caps 61 cover said openings and the upper ends of said shafts.

An inspection of Figs. 5, 6 and 7 will aid in clarifying the foregoing description. For assembly purposes the housing 30 is split along the vertical center line of the dual shafts and has a cover plate portion 62. Screws 63, as shown, maintain the housing parts in assembled relation.

The dual driving shafts 56 are squared or splined from their upper extremities downwardly to an integral collar 64, thence circular as at 65 with their lower extremities being externally threaded as at 66. A pulley 67 is mounted on the hub portion 6 of each plate 7, preferably in different elevations as shown in Fig. 15.

One of said pulleys, that on the left, is driven by its shaft 56 through the medium of a disc nut 68 internally threaded to engage the threaded end 66 of said shaft. The disc nut is provided with an aperture 68a through which extends a pin 69 integral with the pulley. A lock nut 70 and a spacer 71 complete the mounting arrangement.

The right hand construction is similar except that the spacer member 71a is positioned beneath the pulley and has two pins 69a, one of which enters the aperture 68a of the disc nut 68, while the other enters an appropriate depression in the pulley 67. In either arrangement a positive drive is obtained.

The described and illustrated arrangement is preferable to facilitate assembly as well as replacement of the non-metallic pulley facing 12, should it become worn.

A chamber 73 wherein suitable lubricant retaining and dispensing material is contained has a cover 74, removably secured to the carriage 1 by a screw 75. The lubricant may be replenished from time to time through an opening 76 in said cover 74, with ports 77 supplying the lubricant to the moving parts.

A pair of endless flexible belts 78 whose exterior surfaces are abrasively coated as at 79 connect the drive pulleys 67 with the pulleys 13. Replacement of the belts is obviously simple. Due to the resiliency of the belt contacting material of the respective pulleys, no slack take-up contrivance is necessary to maintain the belts taut.

It should now be apparent that with the clutch arrangement described the sharpener assembly may be caused to function simultaneously with the vertical reciprocation of the blade D, when sharpening of the latter is in order.

Novel means are provided to secure the entire sharpening assembly A in an out-of-the-way position during cloth cutting operations. The preferred means, as illustrated more particularly in Fig. 10, includes a clamping member 80, split at

5 81 and secured by a screw 82 to a plate 83, which in turn is secured to the housing 30 by screws 84. The clamping member 80 has a bore 85 slightly larger than the hub 2 of the carriage 1. A bolt 86 threaded into one portion of the split clamp as at 87, and passing freely through a transverse opening 89 in the other portion thereof, is provided with a fixed manually operable handle 89 and a collar 90 engaging the outer surface of the clamp, whereby the hub portion 2 may be clamped or released as desired.

The aforementioned sharpener assembly locking and releasing means is not deemed to require further description, since it is obvious manipulation of the handle 89 away from the machine releases the sharpener assembly, and the opposite manipulation thereof will clamp said assembly in elevated position during cutting operations.

10 20 When it is desired to sharpen the blade, the operator proceeds as follows, without shutting off the power: The assembly clamp is released by turning the handle 89. Then, releasing the locking mechanism N with one hand, the pressure foot bar K, with the sharpener assembly A thereon, is lowered by grasping the member 55, secured to the bar K, with the other hand. When the bar is brought to lowermost position, the roller 43 (Fig. 4) engages the spring 42, thereby connecting the motor to the sharpener. Then by grasping the finger piece 23 (Figs. 8, 9 and 10) the arms or plates 7 are moved from open position (Fig. 9) to operative position (Fig. 8), and by means of the finger extension 4, the sharpener assembly A is reciprocated upwardly and downwardly while the belts engage the opposite sides of the blade D.

15 30 Because of the resiliency and non-circularity of the pulleys 13, a more or less intermittent pressure is applied to opposite sides of the blade at separated points. Since one pulley is mounted at a higher elevation than the other there is never any tendency of the pulleys to bind. Because the pulleys are driven toward one another, no device of any kind is required to maintain the belts in constant yielding engagement with the opposite sides of the knife. The belts 78 take care of this since the "pull" is on the inner stretches thereof tending at all times to bring the pulleys inwardly against the blade.

35 40 As previously described, each pulley has a number of protuberances caused by the insertion of the member 17 in the resilient member 16. It has also been noted that a pair of pulleys having a different number of such protuberances will obtain the best results. The somewhat increased pressure applied when that portion of a belt covering a protuberance engages the blade, has a tendency to momentarily effect the disengagement of the other belt, resulting in a bouncing and sweeping action.

45 55 60 65 70 75 Fig. 8 illustrates this condition, the left hand pulley being in the act of rebounding into engagement with the blade. This view is in perfect scale with the remainder of the views, the only exaggeration being the space X, which in reality is so slight as to defy proper illustration. Shown on a larger scale in Fig. 16 is the condition obtaining a moment later, when a protuberance on the left hand pulley is in the act of effecting a momentary disengagement of the right hand pulley and its belt. The racks 22 are fitted rather loosely to each other so some independent movement of the plates 7 is permitted.

75 80 The irregularity of the pulleys results in a
